PRECISION DETENT SYSTEM

Arling W. Ryberg, Southport, Conn., assignor to The Singer Company, New York, N.Y., a corporation of New Jersey

Filed Sept. 4, 1964, Ser. No. 394,509
8 Claims. (Cl. 74—527)

This invention relates generally to detent systems for rotary members, and more particularly to novel detents that provide precise settings with a high degree of position repeatability.

Variable attenuators for microwave signals of the order of ten kilomegacycles and above, in general practice, are of the lossy-card type mounted within a rotary cylinder. The angular setting of the attenuator cylinder, with respect to fixed coupling wave guides, determines the attenuation effected. Where discrete accurate steps of attenuation are desired, precise and direct angular settings are required. Further, in a practical attenuator, maintenance of its resettability is important. The detent system of this invention is directed to provide a simple, inexpensive and effective solution to such difficult requirements. The elements and features of the novel detent arrangement hereof are applicable to other rotary devices, as well.

Another advantage of the detent mechanism herein set forth is that discrete angular positions of the attenuator that are very close together can be readily accommodated. Each detent arm or follower operates independently. They are displaced laterally and coact with precisely positioned grooves on the circular surface of the drum or cylinder. The novel detent followers hereof are arranged with low internal tensions, to maintain their precision action. Their adjustment in gross and even vernier adjustment is easily accomplished and remain preset. A cantilevered clamp bar is interlinked with each detent follower into a stable array.

The above and other features, advantages and objects of this invention will become more apparent in the following description of an exemplary embodiment thereof, illustrated in the drawings, in which:

FIG. 1 is the front view, partially broken away, of the exemplary microwave attenuator incorporating the invention detents.

FIG. 2 is the rear view of the attenuator of FIG. 1, partially broken away, showing the detents thereof.

FIG. 3 is the top view of the device of FIGS. 1 and 2, partially in section.

FIG. 4 is the cross-sectional view taken along the line 4—4 of FIG. 3, in the direction of the arrows.

FIGS. 5 and 6 are respectively elevational and side views of a detent follower hereof.

FIG. 7 is an enlarged side view of the detent tip.

FIGS. 8 and 9 are respectively plan and side views of the cantilever clamp bar.

FIG. 10 is a perspective illustration of a detent assembly.

The microwave attenuator 15 is a step device with preset precise detented positions selectively attained through knob 16 and shaft 17. The device 15 is enclosed in a frame 18. The control shaft 17 is geared to operating shaft 20 by bevel gears 21, 22 (see FIGS. 3 and 4). The rotary cylinder 25 contains a shaped lossy-card or vane 24 cemented therewithin, in a plane through its axis. Cylinder 25 contains a series of longitudinal surface grooves 26, at one end, that engage with drive gear 27. Gear 27 is rotated by shaft 20, whereby the cylinder 25 is angularly displaced through knob 16.

The angular position or "setting" of the vane 24 determines the resultant attenuation. The central cylinder 25 is joined at each end with fixed transition wave guides 28, 29. The microwave signals to be attenuated are fed

into guide 28, pass through rotary section 25, and out through guide 29; or vice versa. Each transition wave guide contains a central fixed vane (not shown) to complete the attenuation array. The bearings of cylinder 25 are suitably set in its juncture with guide 28, 29, and arranged to also serve as radio frequency chokes.

The predetermined angular settings of rotary cylinder 25 are determined by corresponding longitudinal grooves 30, 30 precisely formed on the cylinder surface. Coacting with respective grooves 30, 30 are associated detent followers 31, 31 that are positioned very accurately, in the invention system. The relatively wide tip 32 of each detent 31 engages its groove 30 in a firm manner, over a substantial extent. This serves to stably hold the attenuator setting. The detent 31' at the left end of FIG. 2 is shown meshed in groove 30'. The detents 31, 31 are longitudinally displaced along the cylinder 25 in individual positions. In this manner, each presetting of the grooves 30, 30 is independently locatable, even in very close angular relation to each other. The exemplary detent followers 31, 31 are of spring steel .025 inch thick, 0.5 inch wide, and about one inch long.

Each detent follower 31, 31 is adjustably supported substantially tangent to the surface of cylinder 25. In the illustrated embodiment the detents 31, 31 are vertically mounted and exposed at the rear of the unit 15, as seen in FIGS. 2, 4 and 10. A horizontally disposed clamp bar 35 contains a lug 33 inserable in an aperture 37 of the detent 31, for holding it by cantilever action. Each clamp bar 35 has a bent central portion for presenting a projecting lug 33 above the support base 34. The tip of machine screw 36 is threaded into opening 37 of bar 35 for securing or loosening its associated detent 31. The cantilever clamp bar 35 is fastened to base 34 by screw 38 at threaded aperture 39 (see FIG. 4.) The clamp bars are made of spring steel to effect spring action in supporting the detents 31, 31. The exemplary clamp bar is .0625 inch thick, .5 inch wide and about 1.25 inch overall.

The bottom region of each detent follower 31 has a rectangular cut-out 40 that rests upon a set-screw 41. The set-screws 41, 41 are threaded into base 34. In this manner the height of the tip 32 of each detent follower 31 above the base 34 is closely adjustable and set, as indicated by the arrows a. The thus preset detents 31, 31 are secured in their respective settings by the pressing down of their corresponding clamp bars 35, 35 through screws 36, 36 as indicated by the arrows b. It is noted that the lugs 33, 33 extending from bars 35, 35 are bent downwardly in apertures 37, 37 of detents 31, 31. This results in a spring bias, holding the detent tips 32, 32 pressed against the surface of the cylinder 25. Bars 35 are held set by the screws 36 in openings 37a.

The detent tips 32, 32 are shaped for accurate seating in their respective surface grooves 30, 30 and still ride over the surface of the cylinder with a minimum of friction. In this way the cylinder 25 is readily rotatable through the knob 16 and associated gearing to the calibrated discrete attenuator settings, wherein the corresponding detent follower 31 engages the groove 30 involved to precisely position the contained vane 24 and firmly maintain its setting. The setting accuracy is accomplished through the minimizing of detent spring tensions in their operation and state.

The adjustment of each detent follower 31, 31 is readily accomplished as follows: The cantilever clamp bar 35 is loosened through its screw 36. The set-screw 41 is then turned to correspondingly raise or lower the detent tip 32 until it seats snugly in its groove 30 on the cylinder 25. The attenuator vane 24 is close to its calibrated angular position while the "gross" adjustments thus far described, are being made. The clamp bar 35 is thereupon tightened through the screw 36 sufficiently for the detent

tip 32 to press firmly in its groove 30. The vernier location of the detent is then accomplished by set-screw 41 adjustment, by slightly angularly displacing the cylinder 25 through the tip 32.

Precise vane 24 positions are indicated by external calibration equipment. The invention detent system effects setting or position "repeatability" over long periods of operation within an accuracy of ± 0.0005 " along the cylinder 25 circumference. An attenuator cylinder 25 of one inch diameter thus affords discrete attenuation steps with excellent repeatability and calibration maintenance in practical field use. The angular location of the index grooves 30, 30 on the cylinder surface corresponds to the desired attenuation steps; the precision setting of the associated detent followers 31, 31 provides the requisite accuracy of the attenuation results.

While the present invention has been illustrated and described in connection with a particular embodiment thereof, it is to be understood that it may be practiced in other forms and arrangements within the broader spirit and scope of the invention as set forth in the following claims.

I claim:

1. A detent system for a rotary member comprising at least one detent section composed of a detent follower coactable with a corresponding groove on the peripheral surface of the member and a clamp bar for maintaining said follower pressed against the member and for engaging it with its associated groove in detenting action for the rotary member, said clamp bar having a projection coupled with said follower and disposed to bias it towards the member, and a set-screw for the vernier adjustment of said follower.

2. A detent system for a rotary member of cylindrical form comprising at least one detent section composed of a detent follower with a lip coactable with a corresponding groove arrayed longitudinally on the peripheral surface of the member and a clamp bar for maintaining the lip of said follower pressed against the cylindrical surface and for engaging it with its associated groove in precise detenting action for the cylindrical member, said clamp bar having a projection coupled with said follower in cantilever array and disposed to bias it towards the member surface, said detent follower being substantially tangent to the member surface, and a set-screw in line with the follower for its vernier adjustment.

3. A detent system for a rotary member of cylindrical form comprising a plurality of detent sections each composed of a detent follower with a lip coactable with a corresponding groove arrayed longitudinally on the

5 peripheral surface of the member and a clamp bar for maintaining the lip of said follower pressed against the cylindrical surface and for engaging it with its associated groove in detenting action for the cylindrical member, each said clamp bar having a projection coupled with its follower and disposed to bias it towards the member surface, and a set-screw for the vernier adjustment of each of said followers.

10 4. A detent system as claimed in claim 3, in which said detent followers are arranged seriatim along the cylindrical surface in a substantially common plane.

15 5. A detent system for a rotary member of cylindrical form comprising a plurality of detent sections each composed of a detent follower of resilient material with a lip of substantial width coactable with a corresponding groove arrayed longitudinally on the peripheral surface of the member and a clamp bar for maintaining the lip of said follower biased towards and pressed against the cylindrical surface and for engaging it with its associated groove in precise detenting action for the cylindrical member.

20 6. A detent system as claimed in claim 5, in which each said clamp bar has a projection coupled with its follower in cantilever array and disposed to hold it against the member surface, said detent followers being substantially tangent to the member surface, and a set-screw in line with each follower for its vernier adjustment of each of said followers.

25 7. A detent system as claimed in claim 5, in which said detent followers are arranged seriatim along the cylindrical surface in a substantially common plane with their corresponding grooves angularly positioned for the desired detenting stops and axially disposed in respective alignment with the followers.

30 8. A detent system as claimed in claim 5, in which said detent followers are arranged seriatim along the cylindrical surface in a substantially common plane with their corresponding grooves angularly positioned for the desired detenting stops and axially disposed in respective alignment with the followers.
